FOOT HOLDER FOR SKIS

Nils Tage Forzelius, Brunemo, Vallentuna, Sweden
Filed Apr. 14, 1965, Ser. No. 448,176
3 Claims. (Cl. 280—11.35)

ABSTRACT OF THE DISCLOSURE

A ski having a boot holder which is provided with opposed side supports having front and rear teeth, a fixed front plate having teeth meshing with some of the front teeth, and a movable rear plate having teeth meshing with some of the rear teeth. Rubber discs and a swingable excenter are used to vary the pressure of the rear plate against the side supports.

This invention relates to skis and refers more particularly to foot holding means for skis. The invention is particularly concerned with a device for adjusting the side holders for ski supports provided with teeth, the adjustment taking place between a fixed toothed plate and a movable toothed plate which can be fixed in a desired position to lock the side supports.

Known constructions of this type cannot be used as safety connections; thus, a skier in the case of a fall could not quickly remove the skis since the holders are blocked by screws. It is known in the art to provide springs which press one of the two toothed plates, namely, the movable plate, against the support, but these springs are used only for the purpose of facilitating the setting of the supports and are not sufficient to hold the supports firmly in their respective positions when the skis are being actually used. Furthermore, the force exerted by the spring or springs upon the support could not be adjusted.

An object of the present invention is to eliminate these drawbacks of prior art constructions.

Other objects will become apparent in the course of the following specification.

In the accomplishment of the objectives of the present invention, it was found desirable to provide resilient means, namely, at least one rubber disc for holding the movable toothed plate against the supports by pressure.

The invention will appear more clearly from the following detailed description when taken in connection with the accompanying drawing showing by way of example, a preferred embodiment of the inventive idea.

In the drawing:

FIGURE 1 is a top view of a device of the present invention, a portion of the cover plate having been removed.

FIGURE 2 is a section along the line II—II of FIGURE 1.

As shown in the drawing, the device of the present invention is fixed upon a ski 10 carrying the support-adjusting members. The device includes a base plate 12 and a cover plate 14. Two foot supports 16 and 18 fit between the plates 12 and 14. A front toothed plate 20 is firmly fixed upon the base plate 12, preferably by spot welding. The base plate 12 along with the front toothed plate 20 and the cover plate 14 are attached to the ski 10 by means of wooden screws 30. A rear movable toothed plate 22 is also located between the plates 12 and 14 along with rubber discs 24 and 26 and a bar 28. The supports 16 and 18 are provided with teeth 32 and 34 at their front and rear edges and these teeth mesh with the teeth 36 and 38, respectively, of the plates 20 and 22 in a manner known per se. The rear movable toothed plate 22 has elongated openings 40 through which screws 30 extend, so that the toothed plate 22 can be shifted in the longitudinal direction of the ski. Furthermore, the movable

2

toothed plate 22 has close to its outer ends rectangular slots 42 extending transversely to the direction of the ski. The base plate has a similar slot 44, while the cover plate 14 has a similar slot 46. However, the slot 46 is shifted rearwardly in relation to the slot 42 of the toothed plate 22 to an extent which corresponds to the extent of movement of the toothed plate 22, so that the plate 22 can move out of engagement with the supports 16 and 18. Therefore, by inserting a screw driver or a similar tool into the slots 46, 42 and 44 and by turning the screw driver, the toothed plate 22 can be moved somewhat rearwardly and thus free the supports 16 and 18, which can then be adjusted so that they will be adapted to the shoe of the skier. Recesses 48 are provided at the rear edge of the toothed plate 22 adjacent the two outer ends thereof, and rubber discs 24 and 26 extend into these recesses. The opposite ends of the rubber discs 24 and 26 engage the bar 28. The rubber discs 24 and 26 are somewhat compressed when the toothed plate 22 is moved rearwardly.

An excenter disc 50 is located adjacent the middle of the bar 28. The disc 50 is swingably mounted by means of a screw or rivet 54 upon an extension 52 constituting a part of the base plate 12. The screw 54 constitutes the axis of rotation of the disc 50. To facilitate the turning of the disc 50, it is provided with an arm 54', which has in the center a substantially rectangular recess. A stop spring 56 is located in this recess and has a curved portion 58 which can fit into any one of the stop openings 60 provided in the extension 52 of the plate 12. The holes 60 are located upon a semi circle so that the excenter disc 50 can be turned to the extent of about 180° and can be held in any desired intermediate position by means of one of the holes 60. Since the bar 28 is loosely mounted between the rubber discs and the excenter disc, this turning of the excenter disc 50 will push the locking bar 28 in its entirety forwardly or rearwardly, whereby the two rubber discs 24 and 26 will be compressed to a greater or lesser extent.

In the position of the excenter disc 50 shown in FIG. 1, the bar 28 is in its rearmost position, so that the rubber discs 24 and 26 are subjected to the least pressure. This makes it possible to release the side supports 16 and 18 from their engagement with the teeth of the two toothed plates 20 and 22, if the force exerted sidewise upon the supports is sufficiently great. Then the supports can be pushed outwardly so that the shoe of the skier can be freed from its engagement with the supports. This setting of the disc 50 is advisable, for example, during slalom skiing or during jumping. On the other hand, during a long run on comparatively flat surfaces, it is advisable to swing the arm 54' all the way to the right (looking in the direction of FIG. 1), since then the supports 16 and 18 as a rule, will not be subjected to side pressures. In the extreme right hand position of the arm 54', the locking bar 28 is pushed forward to the greatest possible extent, so that the rubber discs 24 and 26 are subjected to the greatest compression.

The base plate 12 has a horizontal front end portion 62 which extends somewhat forwardly parallel to the upper surface of the ski. This portion is followed by a vertical portion 64 which extends upwardly preferably to the extent of about two centimeters, as well as a part 66, the upper surface of which is again parallel to the ski surface. Thus, the base plate 12 terminates in a projecting piece 62, 64, 66 which serves as a front support and which engages the tip of the shoe of the skier.

It is apparent that the example described above is capable of many variations and modifications within the scope of the present invention. For example, the two rubber discs 24, 26 may be replaced by a single rubber member which will engage the center of the toothed

3

plate 22. The rubber discs instead of being round as shown, can be of rectangular, trapezoidal or oval shape. It is important, however, that the rubber elements be flat, so that they can be conveniently placed between the base plate 12 and the cover plate 14. The advantage of using rubber elements is that they effectively resist corrosion and thus contribute to the safety and security of the device.

All such and other variations and modifications are to be included within the scope of the present invention.

What is claimed is:

1. In a ski, a foot holding device, comprising, in combination, two opposed supports having teeth on opposite edges thereof, a fixed plate having teeth meshing with some of the teeth of said supports, a movable plate having teeth meshing with other teeth of said supports, two rubber discs engaging said movable plate, a movable bar engaging said rubber discs, and an excenter disc engaging said bar.

2. A device in accordance with claim 1, wherein said

5 bar is of narrow elongated shape and is loosely mounted between said rubber discs and said excenter disc.

3. A device in accordance with claim 1, comprising an arm carried by said excenter disc and means for locking said arm along with said excenter disc in any one of a plurality of positions.
